WICHER VEDDER, OF LYNWOOD, CALIFORNIA, ASSIGNOR OF FIFTY-ONE PER CENT TO
JOHN B. NORTON, OF LOS ANGELES, CALIFORNIA

COMBINATION SEALING STRIP AND STOP FOR DOORS AND WINDOWS

Application filed September 25, 1930. Serial No. 484,343.

My invention relates to weather strips for doors and windows, and is particularly adapted for use on the bottom of swinging doors and windows to exclude air, rain and snow. However, the invention is not limited to doors and windows of the swinging type, but might easily be embodied for use in connection with sliding doors and windows.

It is a principal object of my invention to provide an automatic sealing means adapted to be carried at the bottom of doors and windows (if the doors and windows are of the swinging type) and including a sealing member, operable to automatically project into engagement with the sill of the door or window to seal the space between the bottom thereof and the sill when the door or window is closed and to automatically move into retracted position when the door or window is open.

It is another object of my invention to provide a casing fitted into an elongated recess in the bottom of a door, this casing being adapted to contain all the moving parts of the device.

It is another object of my invention to provide a device of the type described, which includes a sealing member associated with an actuating member in such a manner that movement imparted to the actuating member, by contact with the jamb of a door frame, causes this actuating member to frictionally engage the sealing member with the result that the sealing member moves into engagement with the sill of the doorway, for the purpose described above.

It is another object of my invention to provide a device of the type specified, which includes manually operable means for causing the sealing strip to engage the sill of a door when the door is open.

Another object of my invention is to provide a device of the type above described having manually operable locking means adapted to lock the sealing strip in a position in which it engages the sill of a door to hold the door in open position.

These and other objects will be apparent from a perusal of the following specification,

the accompanying drawings and the appended claims.

Referring to the drawings:

Fig. 1 is a vertical section through the lower portion of a door, showing the sealing means of the invention in an operative position. 55

Fig. 2 is a view similar to Fig. 1 and shows the sealing means in an inoperative position.

Fig. 3 is a cross-sectional view taken as indicated by the line 3—3 of Fig. 1. 60

Fig. 4 is a cross-sectional view taken as indicated by the line 4—4 of Fig. 1.

Fig. 5 is a fragmentary elevational view illustrating the sealing member locking means 65 of the invention.

Referring particularly to Fig. 1, I show a door 11, of the swinging type, hinged as indicated at 12 to the frame 13 of a doorway. Formed in the bottom edge 14 of the door 11 is an elongated, centrally disposed recess 15 extending the full width of the door 11 and adapted to receive a casing 16 in the form of an inverted box, said box having vertical end walls 17, vertical side walls 18, and a horizontal top wall 19. The side walls 18 are provided with horizontally extending flanges 20 secured to the bottom 14, as by screw means 20^a, (shown in Figs. 3 and 4) in such a manner that the open side 21 of the casing 16 is adjacent the sill 22 of the door frame 13. 70

Arranged in vertically sliding engagement with the walls 17 and 18 of the casing 16 is a substantially rectangular plate 25, to the bottom of which is secured a sealing strip 26 85 comprising a strip of rubber, or other compressible material 27, which is molded or otherwise permanently secured to a retaining strip 28. This strip 28 is secured to the plate 25 as by welding or soldering, as shown in Figs. 3 and 4, the sealing strip 26 and the plate 25 comprising the movable sealing member of the device. 90

Extending between the sealing member and a bridge portion 29 of the casing 16 is a tension spring 29^a, which tends to normally hold the sealing member in the retracted position in which it is shown in Fig. 2. 95

Formed in the upper surface of the plate 25 is a longitudinal groove 30 extending in- 100

wardly from one end of the plate, such as the end 31 adjacent the hinged side of the door 11, to a point substantially central of the plate 25, the groove 30 ending in a wall sloping obliquely upward to form a cam face 32, as shown in Figs. 1 and 2. Provided in the bottom surface 33 of the groove 30 and on the cam face 32 is a plurality of drilled holes 34, into which are inserted balls 35, the holes 34 being of such a depth that the balls 35 project upwardly above the surface 33 and the face 32.

Slidably positioned in the groove 30 is an actuating member 40, in the form of a rectangular block, having at the inner end thereof of an obliquely sloping, downwardly facing cam surface 41 adapted to frictionally contact the balls 35 inserted in the cam face 32. The outer end 42 of the actuating member 40 normally projects through an opening 43 in the wall 17 of the casing 16 adjacent the jamb 44 of the door frame 13, as shown in Fig. 2, this end 42 serving as a bumper head adapted to contact the jamb 44 when the door 11 is closed. Resilient means in the form of a tension spring 45 is shown connecting the actuating member 40 and the plate 25, there being a recess 46 provided in the lower surface of the member 40 to accommodate the spring 45 in the manner shown in Figs. 1 and 2. The spring 45, while not essential to the operation of my device, is preferably provided to normally urge the actuating member 40 into its outwardly projecting position as well as to assist the spring 29^a in drawing the plate 25 upwardly within the casing 16.

The outward movement of the actuating member 40 is limited by a bar 50, which is arranged within the casing 16 in such a manner as to contact an upwardly extending abutment 51 provided on the inner end of the member 40 when this member is in its outer or normal position. The bar 50 also serves as a manually operable means of imparting movement to the actuating member 40, this bar being partly cylindrical, as shown in Fig. 4, so that said bar is rotatable as well as longitudinally slidable relative to the casing 16. Extending transversely outward from one side of the bar 50 is a pin 52, which projects through an opening 52^a in the casing 16 and the door 11, and is provided with a grasping knob 53 for the manual manipulation thereof. A plate 54 secured to the door 11, as by screws 55, is provided with notches 56 adapted for the reception of the pin 52 for a purpose to be described later.

The upper surface 60 of the actuating member 40 is preferably provided with a plurality of drilled holes 61 in which are placed balls 62 adapted to contact the wall 19 of the casing 16 to reduce friction between the casing 16 and the actuating member 40.

The operation of my invention is as follows:

When the door 11 is open the movable parts of the device are allowed to assume their respective normal positions indicated in Fig. 2, at which time the sealing strip 26 is clear of the sill 22, and the bumper head 42 of the actuating member 40 projects outwardly beyond the end 17 of the casing 16, as described.

When the door 11 is moved towards its closed position the bumper head 42 contacts the jamb 44 of the door frame 13 and the actuating member 40 is pushed inwardly into the position in which it is shown in Fig. 1, with the result that the sealing member is forced downwardly, due to the camming action between the cam face 32 and the cam surface 41. It will be seen that when the sealing member 26 is in its lowermost position, as indicated in Fig. 1, the rubber strip 27 contacts the sill 22 in such a manner as to exclude air drafts, rain or snow. It will be clearly understood that when the door 11 is opened the sealing member will move upwardly under the influence of the spring 29^a, and the actuating member 40 will be forced outwardly by the camming action between the cam face 32 and the cam surface 41, assisted by the spring 45, into its normal position.

Should it be desired to hold the door 11 in open position, the grasping knob 53 may be raised into the position indicated by dotted line 70 of Fig. 4, so that the pin 52 is clear of the notches 56. The knob 53 is then drawn in the direction of the arrow 71 of Figs. 1, 2 and 5, motion being imparted to the actuating member 40 in the same direction, by reason of the contact between the bar 50 and the abutment 51, this movement of the actuating member 40 actuating the sealing member in the manner described above. When the bar 50 is moved in the direction of the arrow 71 sufficiently to cause the rubber strip 27 to pressurely engage the sill 22, the grasping knob 53 may be depressed so that the pin 52 engages one of the notches 56, which serves to lock all the moving parts of the device in their respective operative positions. The release of the door is accomplished by simply raising the grasping knob 53 so that the pin 52 clears the notches 56, whereupon the movable parts of the device automatically assume their normal positions, as above described.

Although I have herein shown and described a single embodiment of my invention it should be understood that I am aware various features thereof might be changed and numerous embodiments thereof might be devised without departing from the spirit and scope of my invention.

I claim as my invention:

1. In a sealing device of the character described, the combination of: a closure member adapted to close an opening; a recess formed in an edge of said closure member; a sealing member positioned within said recess and movable to engage an adjacent wall of

5 said opening; an engageable face provided on said sealing member; an actuating member operable to automatically engage said face coincident with the closing of said closure member, whereby said sealing member will be moved to engage said wall; and manually operable means for causing said sealing member to engage said wall when said closure member is open, for the purpose of holding 10 said closure member in open position.

10 2. In a sealing device of the character described, the combination of: a closure member adapted to close an opening; a recess formed in an edge of said closure member; a sealing member positioned within said recess and movable to engage an adjacent wall of said opening; an engageable face provided on said sealing member; an actuating member operable to automatically move transversely with respect to the direction of movement of said sealing member to engage said face coincident with the closing of said closure member, whereby said sealing member will be moved to engage said wall; and manually operable means for causing said sealing member to engage said wall when said closure member is open, for the purpose of holding said closure member in open position.

15 3. In a sealing device of the character described, the combination of: a closure member adapted to close an opening; an elongated recess formed in an edge of said closure member and adapted to receive a casing having an aperture therein; a sealing member positioned in said casing and operable to move outwardly through said aperture to engage an adjacent wall of said opening; means for normally urging said sealing member inwardly in said casing; an engageable face provided on said sealing member; an actuating member movable transversely with respect to the direction of movement of said sealing member; an engaging surface provided on said actuating member and adapted to engage said face; a bumper head provided on said actuating member and normally extending beyond an end of said casing to engage an adjacent wall of said opening when said closure member is moved into closed position, whereby said actuating member is moved, thus causing said surface to engage said face so as to move said sealing member outwardly into engagement with said first mentioned wall; and manually operable means for causing said sealing member to engage said first mentioned wall when said closure member is open, for the purpose of holding said closure member in open position.

20 4. In a sealing device of the character described, the combination of: a closure member adapted to close an opening; an elongated recess formed in an edge of said closure member and adapted to receive a casing having an aperture therein; a sealing member positioned in said casing and operable to move

outwardly through said aperture to engage an adjacent wall of said opening; means for normally urging said sealing member inwardly in said casing; a cam face provided on said sealing member; an actuating member movable transversely with respect to the direction of movement of said sealing member; a cam surface provided on said actuating member and adapted to engage said cam face; a bumper head provided on said actuating member and normally extending beyond an end of said casing to engage an adjacent wall of said opening when said closure member is moved into closed position, whereby said actuating member is moved, thus causing said cam surface to engage said cam face so as to move said sealing member outwardly into engagement with said first mentioned wall; and manually operable means for causing said sealing member to engage said first mentioned wall when said closure member is open, for the purpose of holding said closure member in open position.

25 5. In a sealing device of the character described, the combination of: a closure member adapted to close an opening; an elongated recess formed in an edge of said closure member and adapted to receive a casing having an aperture therein; a sealing member positioned in said casing and operable to move outwardly through said aperture to engage an adjacent wall of said opening; means for normally urging said sealing member inwardly in said casing; a cam face provided on said sealing member; an actuating member movable transversely with respect to the direction of movement of said sealing member; a cam surface provided on said actuating member and adapted to engage said cam face; a bumper head provided on said actuating member and normally extending beyond an end of said casing to engage an adjacent wall of said opening when said closure member is moved into closed position, whereby said actuating member is moved, thus causing said cam surface to engage said cam face so as to move said sealing member outwardly into engagement with said first mentioned wall; means for returning said actuating member to its normal position; and manually operable means for causing said sealing member to engage said first mentioned wall when said closure member is open, for the purpose of holding said closure member in open position.

30 6. In a sealing device of the character described, the combination of: a closure member adapted to close an opening; an elongated recess formed in an edge of said closure member and adapted to receive a casing having an aperture therein; a sealing member positioned in said casing and operable to move outwardly through said aperture to engage an adjacent wall of said opening; means for normally urging said seal-

ing member inwardly in said casing; an engageable face provided on said sealing member; an actuating member movable transversely with respect to the direction of movement of said sealing member; an engaging surface provided on said actuating member and adapted to engage said engageable face; a bumper head provided on said actuating member and normally extending beyond an end of said casing to engage an adjacent wall of said opening when said closure member is moved into closed position, whereby said actuating member is moved, thus causing said surface to engage said face so as to move said sealing member outwardly into engagement with said first mentioned wall; means for returning said actuating member to its normal position; an operating block arranged within said casing so as to be slidable longitudinally relative to said casing and said actuating member, said operating block being adapted to contact an abutment formed on said actuating member; a grasping knob associated with said block and projecting exteriorly of said closure member, said knob being manually operable to cause said block to engage said abutment to move said actuating member, whereby said surface engages said face to move said sealing member outwardly into engagement with said first mentioned wall; and locking means associated with said grasping knob to lock said movable parts in said last named position, for the purpose of holding said closure member in open position.

In testimony whereof, I have hereunto set my hand at Los Angeles, California, this 22nd day of September, 1930.

WICHER VEDDER.
